UNITED STATES PATENT OFFICE.

ARMIN STRAUSS, OF ROCHESTER, NEW YORK.

SNOW HANDLING AND REMOVING MEANS.

974,306.

Specification of Letters Patent.

Patented Nov. 1, 1910.

Application filed April 13, 1910. Serial No. 555,172.

To all whom it may concern:

Be it known that I, ARMIN STRAUSS, a citizen of the United States, and a resident of Rochester, in the county of Monroe and 5 State of New York, have invented a new and Improved Snow Handling and Removing Means, of which the following is a specification.

This invention relates to means for removing, preferably, masses or piles of snow 10 from public streets as will be explained.

The usual method of removing snow from streets consists in loading the same upon sleighs or wagons and drawing it to a suitable locality where it may be dumped or unloaded. In many towns and cities there is 15 not afforded a suitable dumping place where the snow may be unloaded or dumped without involving considerable labor and expense and under any circumstances the loading or unloading of the snow and drawing it to such a dumping place involves a large amount of labor and expense.

My present invention comprises means for 25 scooping up the snow and delivering it to a suitably heated chamber where it is melted and the melted snow, in the form of water, is delivered from the machine to the streets either at the location of the device or it may 30 be conveyed by means of hose to a suitable sewer opening. In accordance with my invention, then, I provide a melting chamber suitably mounted upon a truck provided with a fireplace or furnace a part of the heat 35 from which may be used to generate steam in a suitable boiler for propelling the apparatus and for operating the revolving blades which I prefer to make use of in order to more finely divide the masses of snow and 40 keep the same in motion so that it may be more rapidly melted. From this same source of power suitable connections are made for operating the scoop used to scoop up the snow and to deliver it to the melting chamber.

Very obviously any source of power may 45 be used for propelling the whole device along the street or roadway and for operating the revolving blades and also for operating the scoop although I have found it 50 desirable to make use of a steam engine for this purpose although gas engines or internal combustion engines may be substituted therefor, or an electric motor, as desired.

In the accompanying drawings I have 55 shown a preferred embodiment of my invention in which the steam engine is made use of as the source of power and the steam therefor is generated in a suitable boiler heated from the furnace for maintaining the 60 melting chamber at a proper temperature to melt the snow.

The accompanying drawings illustrating 65 such an embodiment of my invention are as follows;

Figure 1 is a side view and Fig. 2 is a central longitudinal sectional view of the machine. Fig. 3 shows the steering mechanism in plan view. Fig. 4 is a front view and Fig. 5 is a rear view of the machine. Figs. 70 6, 8 and 9 are front, rear and side views, respectively, of the case containing the melting chamber and the furnace. Fig. 7 is a transverse sectional view taken just to the rear of the series of revolving snow cutting 75 blades seen in Fig. 2. Fig. 10 is a view from the right, of Fig. 5, of a part of the actuating mechanism for the snow scoop, as will be explained. Fig. 11 is a sectional detail view of the clutch mechanism on the stud 8 80 on one side of the machine.

Similar characters of reference refer to similar parts throughout the several figures of the drawings.

Referring to the drawings. My machine 85 is supported from front and rear wheels w^1 and w , respectively, through the medium of the curved channeled beams D supported at their rear ends from the rear axle F. These channeled beams D are extended to the rear 90 and connected by a cross beam d^1 , and by a platform D^1 which is provided to receive the engine Z, and within this inclosure, thus formed, a suitable quantity of coal may be carried for the purpose of supplying the 95 furnace of the machine. The channeled beams D are curved upwardly at their forward ends and connected by a cross bar f beneath which is secured the upper member of the fifth wheel f^1 , the lower member being connected with the axle F^1 ; and for swinging the axle F^1 there is provided a chain or cable m engaging through suitable eyes on the axle F^1 and wound taut around the shaft M having bearings in the channeled beams D and provided on the right hand side of the machine with a worm gear m^1 engaged by a worm m^2 on the shaft m^1 100 105

revolubly supported near the worm m^6 in a suitable bearing m^3 secured to the right hand channeled beam D. The shaft or steering rod m^1 carries, at its rear end, an operating wheel m^2 , located to be accessible to the operator, for the purpose of steering the machine. This wheel m^2 and shaft m^1 are omitted from the other figures of drawing to avoid confusion, the operation of such mechanism being thoroughly well known in the arts, it is not necessary to further illustrate or show the same.

Between and secured to the forward ends of the beams D there extends a connecting plate D^2 comprising a suitable stop plate adapted to support the snow scoop E in its lowermost position and resting on and secured to the brackets d^8 . Between and supported from the beams D there is seen an obliquely disposed cross bar d^2 adapted to support the casing A containing the heating chamber and the revolving blades and also the boiler and also carrying a grating H comprising the fire-bed for the heating furnace. This casing A at its rear end rests on the channeled cross bar d . This casing A is provided on its sides with double walls a^7 and a^8 spaced apart a short distance and with the intervening space filled with any suitable nonconducting medium for heat such as sand as seen at h in Fig. 7. With this case A there is located a melting chamber having the curved bottom wall A^1 and within this latter chamber there is revolubly supported upon the shaft S^1 the cutting blades y . The shaft S^1 extends through the side walls of the melting chamber and also through the side walls of the case A and is revolubly supported therein. The side walls a^8 of the melting chamber are spaced apart from and within the side walls of the casing A to permit the heat from the furnace to pass entirely around the melting chamber on its sides. The top of the casing is seen at a . The front of the casing is formed in two sections, an obliquely and downwardly extending section a^1 and a short vertically disposed section a^2 and beneath which latter there extends obliquely to the rear, a bottom or lower wall a^3 and to the rear of that and connecting therewith is seen the bottom of the ash pit a^4 while the rear wall of the casing A is seen at a^5 .

Pipes j are suitably connected to the melting chamber through its side walls and at the openings o , and such pipes extend outwardly through the side walls of the casing A and may be provided with suitable valves as j^1 adapted, if desired, to receive suitable coupling members from a hose such as n^1 which may be wound upon the reel n revolubly supported upon the shaft N, which, in turn may be squared off to receive a suitable crank for winding the hose n^1 up when not in use. It is usually unnecessary to use such

a hose as the water from the melted snow may be permitted to pass out upon the road-bed or pavement but sometimes I have found it desirable to make use of the hose to convey the water to a sewer opening.

Beneath the melting chamber are located the grate bars H upon suitable supports h^2 secured to the lower front and rear inclined portions of the under side of the casing A and beneath these grate bars H there is supported the dump door C² suitably hinged at c^1 to the bottom wall a^3 of the casing. This dumping door C² is normally held in closed position by means of the bar L extending thereunder and pivotally supported in the ear i secured to the wall a^3 and provided with an extension i^1 having a crank-like projection adapted to be engaged by the hook i^2 pivotally supported from the side wall of casing A as indicated in Fig. 9.

The fire chamber is lined, on the inside, with suitable fire brick h^1 to properly protect the same and at the rear end of the fire chamber but through the side walls of the casing A there are formed openings o^1 through which extend pipes J for providing suitable draft and for the escape of smoke from the furnace.

In the rear of the casing A and above the furnace and also to the rear of the melting chamber is seen a boiler comprising drums B and B¹ connected by suitable water pipes b suitably supported in the casing in any desired way, not shown, and provided with a steam dome b¹ and having a feed pipe b² for supplying steam to the cylinder of the engine Z, the motion of the piston of which is transmitted to the engine shaft S² through the medium of the crank z¹ thereon and the connecting link or pitman z. A branch of the pipe b², as seen at b³ is adapted to supply an injector, B² taking the water supply through pipes b⁴ from the water at the bottom of the melting chamber and connected through the pipe b⁵ to the boiler in the usual way.

The snow scoop E is pivotally hinged at its upper end, as seen, to brackets e³ secured to the portion a^2 of the wall of the casing A. The side walls e of the scoop E are adapted to hold and retain between them the snow that is scooped up and a U shaped bar e¹ extends across and between the sides e and is secured thereto and to this bar e¹, near its middle, there is secured a cable or chain U which also engages through and is secured to the eye-bar e² projecting outwardly and upwardly from the door C, hinged at c as seen to the top of the casing A, in such a way that, when such cable or chain U is drawn to the right, with reference to Fig. 1, the scoop E is raised to the position indicated in dotted lines at E¹ and the door C is raised to the position indicated in dotted lines at C¹, whereby the snow scooped up by

the scoop E is delivered through the opening O for the door C into the melting chamber and is continuously cut up and moved to the rear thereof by means of the revolving 5 blades y. The cable or chain U may extend between suitable rollers v revolvably supported from ears or arms V secured to the top of the casing A. Arms V¹ secured to the top of the steam dome b¹ of the boiler B are also 10 provided with rollers v and also with a rearwardly extending channelled arm V² in which the cable or chain U is adapted to move. This cable or chain U is secured, at its right hand end, to the pin u secured in the gear 15 wheel G¹ revolvably supported upon the stud s³ and engaged by a smaller spur gear g⁶ revolvably supported upon a shaft s², extending through the L shaped bearing arm k, and carrying on its forward end the beveled 20 gear g⁶ meshing in turn with a similar beveled gear g⁴ on the shaft S. The gear g⁶ is freely revolvable upon this shaft s² except when clutched thereto by means of the clutch T engaged and operated by the bifurcated 25 end of the lever t pivotally supported in turn in the ears t² and carrying the handle t¹. A main shaft S is suitably mounted in bearings k¹ secured to the rear end of the casing A and carries outside of such bearings spur gears g¹ each engaging a spur gear g² revolvable upon a sleeve s¹ revolvable also on a stud s extending outwardly from the side of the casing A. Each sleeve s¹ carries a spur gear g³ and has splined thereon the 30 toothed clutch r adapted to be operated in the manner to be explained to engage the gear wheel g². The gears g³ mesh with the gear wheels G preferably secured to the main drive wheels w. Each gear g³ may be 35 clutched to its corresponding gear g² through the mechanism of the clutch levers r² and the links r¹ connecting their lower ends with the disk R, pivotally supported at its center and carrying the operating hand r³. The 40 shaft S carries a band or sprocket wheel p from which, by means of the band or sprocket P motion is communicated to the pulley p¹ on the end of the shaft S¹, imparting thereto rotation in the direction indicated by the arrow in Fig. 1. One of the 45 gears g¹, preferably the one to the left of the operator on the platform D¹, is engaged by the gear g on the drive shaft S² of the engine which it will at once be understood is 50 shown only diagrammatically to illustrate a source of power.

At O¹ is seen an opening closed by the door C¹ for stoking the furnace.

In operating my machine the fire is built 60 in the usual way in the furnace on the grates H and when the heat thereof has generated sufficient steam in the boiler B the engine may be started in the usual way and by operating the lever r³ the machine may be propelled along the road with the scoop E en-

gaging into a pile or heap of snow and then by operating the lever t¹ the door C and the scoop E are raised to the positions indicated in Fig. 1 at C¹ and E¹ causing the snow in the scoop E to be discharged into the melting chamber and it is then finely divided and forced to the rear by means of the revolving blades or arms y on the shaft S¹. 70

By operating the steering wheel m², as indicated in Fig. 3, the machine may be directed so as to cause the scoop E to properly engage into the piles or heaps of snow and the water from the melted snow runs out through the pipes j and the valves j¹ and may be discharged upon the road bed or 75 pavement or when desired the hose n¹ may be attached to the nozzles of the faucets j¹ and the water led therethrough to any desired location to avoid unnecessary flooding of the road bed or pavement and by the 80 manipulation of the levers r² and t¹ and by operating the steering wheel m² the proper control of the machine and the several parts thereof may be maintained. 85

It is to be understood that when the engine 90 or motor is running the scoop E may be operated independently of the movement of the machine upon the road bed and that the machine may be progressed along the road bed independently of the operation of the 95 scoop E.

From the foregoing description of the construction and method of operating the several parts of my machine it is believed that the operation and method of using the 100 same is sufficiently clear to call for no further consideration herein.

What I claim is:

1. Coöperatively combined for the purpose described, a truck adapted to move along the road bed; a melting chamber, and means for heating the same, provided with suitable discharge opening or openings for the water from the melted snow; an opening through the wall of the melting chamber; a scoop for engaging the snow in front of the truck pivotally supported in alinement with the opening for receiving the snow in the melting chamber and means for swinging the snow scoop to discharge the snow therefrom into the melting chamber. 105 110 115

2. Coöperatively combined for the purpose described, a truck adapted to move along the road bed; a melting chamber, and means for heating the same, provided with suitable discharge opening or openings for the water from the melted snow; an opening through the wall of the melting chamber provided with a suitable closure or door; a scoop for engaging the snow in front of the truck pivotally supported in alinement with the opening for receiving the snow in the melting chamber and means for opening the door to the melting chamber and swinging the snow scoop to discharge the snow therefrom into 120 125 130

the melting chamber and operative connections between such door and such snow scoop to coöperatively time their movements.

3. Coöperatively combined for the purpose described, a truck adapted to move along the road bed; a melting chamber, and means for heating the same, provided with suitable discharge opening or openings for the water from the melted snow; an opening through the wall of the melting chamber provided with a suitable closure or door; a scoop for engaging the snow in front of the truck pivotally supported in alinement with the opening for receiving the snow in the melting chamber and means for opening the door to the melting chamber and for swinging the snow scoop to discharge the snow therefrom in the melting chamber.

4. Coöperatively combined for the purpose described, a truck adapted to move along the road bed; a melting chamber, and means for heating the same, provided with suitable discharge opening or openings for the water from the melted snow; an opening through the wall of the melting chamber; a series of revolubly supported blades in the melting chamber for engaging and dividing the snow and means for revolving the same; a scoop for engaging the snow in front of the truck pivotally supported in alinement with the opening for receiving the snow in the melting chamber and means for swinging the snow scoop to discharge the snow therefrom into the melting chamber.

5. Coöperatively combined for the purpose described, a truck adapted to move along the road bed; a melting chamber, and means for heating the same, provided with suitable discharge opening or openings for the water from the melted snow; an opening through the wall of the melting chamber provided with a suitable closure or door; a series of revolubly supported blades in the melting chamber for engaging and dividing the snow and means for revolving the same; a scoop for engaging the snow in front of the truck pivotally supported in alinement with the opening for receiving the snow in the melting chamber and means for opening the door to the melting chamber and swinging the snow scoop to discharge the snow therefrom into the melting chamber and operative connections between such door and such snow scoop to coöperatively time their movements.

6. Coöperatively combined for the purpose described, a truck adapted to move along the road bed; a melting chamber, and means for heating the same, provided with suitable discharge opening or openings for the water from the melted snow; an opening through the wall of the melting chamber provided with a suitable closure or door; a series of revolubly supported blades in the melting chamber for engaging and dividing

the snow and means for revolving the same; a scoop for engaging the snow in front of the truck pivotally supported in alinement with the opening for receiving the snow in the melting chamber and means for opening the door to the melting chamber and for swinging the snow scoop to discharge the snow therefrom in the melting chamber.

7. Coöperatively combined for the purpose described, a truck adapted to move along the road bed provided with means for propelling the same; a melting chamber, and means for heating the same, provided with suitable discharge opening or openings for the water from the melted snow; an opening through the wall of the melting chamber; a scoop for engaging the snow in front of the truck pivotally supported in alinement with the opening for receiving the snow in the melting chamber and means for swinging the snow scoop to discharge the snow therefrom into the melting chamber.

8. Coöperatively combined for the purpose described, a truck adapted to move along the road bed provided with means for propelling the same; a melting chamber, and means for heating the same, provided with suitable discharge opening or openings for the water from the melted snow; an opening through the wall of the melting chamber; a series of revolubly supported blades in the melting chamber for engaging and dividing the snow and means for revolving the same; a scoop for engaging the snow in front of the truck pivotally supported in alinement with the opening for receiving the snow in the melting chamber and means for swinging the snow scoop to discharge the snow therefrom into the melting chamber.

9. Coöperatively combined for the purpose described, a truck adapted to move along the road bed provided with means for propelling the same; a melting chamber, and means for heating the same, provided with suitable discharge opening or openings for the water from the melted snow; an opening through the wall of the melting chamber provided with a suitable closure or door; a scoop for engaging the snow in front of the truck pivotally supported in alinement with the opening for receiving the snow in the melting chamber and means for opening the door to the melting chamber and swinging the snow scoop to discharge the snow therefrom into the melting chamber and operative connections between such door and such snow scoop to coöperatively time their movements.

10. Coöperatively combined for the purpose described, a truck adapted to move along the road bed provided with means for propelling the same; a melting chamber, and means for heating the same, provided with suitable discharge opening or openings for

the water from the melted snow; an opening through the wall of the melting chamber provided with a suitable closure or door; a series of revolubly supported blades in the melting chamber for engaging and dividing the snow and means for revolving the same; a scoop for engaging the snow in front of the truck pivotally supported in alinement with the opening for receiving the snow in the 10 melting chamber and means for opening the

door to the melting chamber and swinging the snow scoop to discharge the snow there from into the melting chamber and operative connections between such door and such snow scoop to coöperatively time their movements. 15
